METHOD FOR FLASH DISTILLATION OF OILS

Filed Jan. 22, 1929

FIG. 2

FIG. 1

Inventor
Nathaniel E. Loomis
By his Attorney Attaway

UNITED STATES PATENT OFFICE

NATHANIEL E. LOOMIS, OF WESTFIELD, NEW JERSEY, ASSIGNOR TO STANDARD OIL DEVELOPMENT COMPANY, A CORPORATION OF DELAWARE

METHOD FOR FLASH DISTILLATION OF OILS

Application filed January 22, 1929. Serial No. 334,153.

This invention relates to the art of heat treating hydrocarbon material, more particularly to the distillation or cracking of mineral oils, and will be fully understood from the following description, read in conjunction with the accompanying drawing, in which

Fig. 1 is a vertical section of a preferred form of apparatus for carrying out my invention, and

Fig. 2 illustrates the use of the apparatus shown in Fig. 1 in conjunction with cracking apparatus.

Referring to Fig. 1, hydrocarbon material to be treated (e. g. a heavy oil containing coke-forming bodies) is drawn from a source of supply A by a pump 2 and forced thru a heating coil 12, whence it passes by pipe 13 and nozzle 14 into the flash drum or evaporator 15. The drum 15 may be an ordinary shell still provided at each end with removable manheads 16 and vapor draw off line 17. A slightly lower pressure, not substantially above atmospheric and preferably a partial vacuum is maintained in the drum 15 whereby the hydrocarbon material, heated to its vaporization point in the coil, tends to immediately flash into vapor form as it is discharged from the nozzle 14. Vapors pass off from the drum 15 thru a vapor line 17 to a condenser 18 whence the condensate passes by pipe 20 provided with a valve 19 to a receiver 21 provided with a condensate draw-off connection 21a and a valved pipe 21b leading to a source of suction.

In flashing heavy residuum to coke, difficulty is experienced in securing a product sufficiently free of oil to be cleaned readily from the evaporator or to be pulverized for powdered fuel. This is due to the difficulty of maintaining a sufficiently high temperature in the evaporator to completely vaporize all of the volatile matter. Some heat may be applied externally to the evaporator, but this is generally undesirable because it makes the coke hard to remove.

In my improved method, I correct the heat deficiency by introducing a relatively small amount of air into the evaporator 15,

whereby a partial combustion of the hydrocarbon material is effected and the temperature in the evaporator is increased sufficiently to produce a substantially oil-free coke deposit.

In the preferred construction of my apparatus, I have shown the air introduced thru pipe 22 which discharges into the atomizing nozzle 14 preferably at a point such that little or no contact between the hydrocarbon material and the air is effected in the nozzle itself. I may, however, introduce the air near the bottom of the evaporator 15 by means of a perforated pipe or thru a false bottom provided with suitable perforations. Other modifications may suggest themselves for this purpose and I contemplate any means of securing intimate contact between an oxygen containing gas and the heated hydrocarbon material in a flash chamber as coming within the scope of my invention.

My invention is particularly applicable to the treatment of tar residue from cracking operations. Referring to Fig. 2, I have shown my invention as used in conjunction with a cracking apparatus of the tube and tank type.

Stock to be cracked, for instance, gas oil, is pumped by pump 2 from a source of supply A to a cracking coil 1, from which the heated products are discharged by a pipe 3 into the soaking drum or digester 4 where, due to the greatly reduced velocity of flow thru the drum, the greater portion of the cracking occurs. The cracked products are withdrawn from the soaking drum 4 by a pipe 5, preferably provided with a valve 5a, and discharged into a separating chamber 6. A lower pressure may be maintained in the separator 6 than is maintained in the soaking drum 4, whereby light fractions are vaporized and drawn off thru vapor line 7 to a suitable condenser 8, the condensate passing thru line 9 provided with valve 9a to a receiving drum 10.

Unvaporized products separated in the chamber 6 are withdrawn thru a line 11 provided with a throttle valve 13a and 100

passed thru heating coil 12 whence they are discharged by pipe 13 terminating in a nozzle 14, into an evaporator 15. Light fractions are vaporized in the evaporator 15, which is maintained under a slightly lower pressure not substantially greater than atmospheric and preferably a partial vacuum, and are withdrawn thru vapor line 17 to a suitable condenser 18. Condensate passes from the condenser 18 thru pipe 20 provided with a valve 19 to a receiving drum 21.

The evaporator 15 is provided with removable manheads 16 to render the drum accessible for cleaning out. Air is supplied to the nozzle 14 thru a line 22, as described above, or by any other means so as to insure intimate contact with the hot liquid entering the drum, whereby sufficient heat is generated to completely vaporize all the volatile products and leave a dry coke residue.

I may, if desired, provide a lining of refractory material in the flash chamber, altho this is not usually necessary if the amount of air admitted be carefully regulated.

It will be understood that a pump, not shown, may be interposed between the separator 6 and the heating coil 12 in case the pressure in the separator is not sufficient to force the tarry residue thru the coil.

The following example is illustrative of my invention.

Tar residue from a cracking process, having a viscosity of about 50 sec. Furol at 210° F., and boiling at substantially above 500° F., is drawn from a storage tank, or preferably without cooling from the vapor separator 6 of a cracking apparatus, as shown in Fig. 2, and is passed thru a heating coil 12 in which it is heated to 750-800° F. In this heating stage I may maintain considerable pressure upon the material being treated, say 150 pounds per square inch or more, but preferably I maintain only such pressure as is necessary to force the material thru the coil and deliver the heated material to the evaporator. The evaporator is maintained at atmospheric or slightly reduced pressure. The heated material is discharged in atomized form into the vapor space of the evaporator thru an injector nozzle of which different types are well known, together with a small amount of air. I prefer to introduce the air at or near the point at which the heated material is introduced, but if this method is used, care must be taken to insure that combustion does not occur within the injector nozzle itself as the temperatures produced may result in injury or destruction of the nozzle.

The amount of air introduced is carefully regulated to maintain a temperature in the evaporator of approximately 850° F. At this temperature all vaporizable constituents are volatilized and withdrawn in the

form of vapors. The coke-forming bodies in the tar are precipitated as a hard, dry coky residue which may be easily removed at suitable intervals and which is well adapted to be pulverized for use as powdered fuel, in the manufacture of briquettes, or for other purposes.

It will be understood that while I have described only two forms in which my invention may be used, other forms and modifications are contemplated which come within the spirit and scope of the invention.

I claim:

1. The method of distilling heavy hydrocarbon material containing coke forming bodies, which comprises passing the material in a restricted stream through a heating zone, reducing the pressure, atomizing the material into a vaporizing zone, injecting sufficient oxidizing gas into the atomized material in concurrent flow therewith, to effect the partial combustion necessary for volatilization of substantially all volatile components, and withdrawing the vaporized products, whereby substantially oil-free coke residue is obtained in the said vaporizing zone.

2. The method of distilling heavy hydrocarbon material containing coke forming bodies, which comprises passing the material in a restricted stream through a heating zone, reducing the pressure, atomizing the material into a vaporizing zone, injecting air into the atomized material in concurrent flow therewith, to effect the partial combustion necessary for volatilization of substantially all volatile components and withdrawing the vaporized products, whereby substantially oil-free coke residue is obtained in the said vaporizing zone.

3. The process of recovering oil-free coke from heavy residuum resulting from the cracking of a hydrocarbon oil, which comprises passing the residuum in a restricted stream through a heating zone, reducing the pressure, atomizing the residuum into a vaporizing zone, injecting sufficient air into the atomized residuum in concurrent flow therewith, to effect the partial combustion necessary for volatilization of substantially all volatile components, and withdrawing the vaporized products, whereby substantially oil-free coke residue is obtained in the said vaporizing zone.
